UNITED STATES PATENT OFFICE.

NICHOLAS BENENATI, OF NEW YORK, N. Y.

STEAM PRESSING APPARATUS.

Application filed August 18, 1926. Serial No. 129,994.

My invention relates to steam pressing apparatus and more particularly to an apparatus for pressing hatbands and ties and like articles of narrow width and relatively long length. The apparatus seeks to avoid the use of heated irons, as such irons put a glossy finish on the bands or ties, and the usual apparatus for pressing suits is too cumbersome to press articles of this nature. The present invention therefore has for an object the provision of a small pressing apparatus for pressing articles of relatively narrow width, with means for heating the apparatus by means of steam and from which steam is emitted during the pressing operation, against the article being pressed, which facilitates the pressing operation.

Still other objects in view are means for drying the steam as it is admitted to the heating apparatus and for separating the condensation from the steam as it is formed in the apparatus.

The invention is shown in the accompanying drawings, in which

Figure 1 is a view in elevation, of my invention applied to a steam boiler;

Figure 2 is a view showing a cross section of a portion of the apparatus;

Figure 3 is a cross sectional view on the line 3—3 of Figure 1, illustrating in addition how the apparatus is used in pressing an article.

In the accompanying drawings the pressing apparatus 1 is shown connected to a steam boiler 2 by suitable piping 3, and a valve 4 to permit steam from the boiler 2 to enter the pressing apparatus 1 as desired. The boiler 2 may be of any type of steam boiler used in cleaning and pressing establishments, for supplying steam or hot water, the connecting pipe 3 preferably being coupled to the boiler, adjacent the top thereof, so that the steam is as dry as possible when admitted to the pressing apparatus.

The pressing apparatus 1 consists of a cylindrically shaped casing or drum 5 formed into an upper or dry steam chamber 6 and a lower or wet steam chamber 7 by a horizontal partition or wall 8 with a communicating passageway 9 at one end. The chamber 7 receives the steam from the boiler through a port 15, in a more or less wet or saturated condition, and in order to moisten the article to be pressed with dry, hot steam, it is desirable that the excessive moisture in the steam be removed. For this reason the pressing

apparatus 1 is provided with the chambers 6 and 7 respectively, the lower chamber 7 receiving the steam in a wet condition and in which a consequent expansion in volume takes place with a reduction in temperature and pressure, thereby causing the moisture in the steam to condense and the condensate to collect in the bottom of the chamber. A drip-cock 10 connected to the apparatus at 11 is adapted to take off such condensation and if it is desired such drip-cock may be opened to a slight extent whereby such condensation will be blown out therethrough as it is formed. The steam then passes through the passageway 9 to the chamber 6 in a relatively dry condition and is emitted therefrom through the small openings 12 arranged in the top thereof, longitudinally, from side to side of the casing or drum. These openings are relatively small so that as little moisture as possible will pass therethrough with the steam, any moisture being present in the dry chamber gravitating to the lower chamber by means of the passageway 9. The ends of the drum 5 are provided with raised beads 13 to press and straighten the lateral edges of the article when being pressed and to retain the article therebetween. The steam thus admitted to the pressing apparatus heats the apparatus to approximately the temperature of the steam, the casing or drum 5 being formed of any desired metal which will readily transmit the heat from the steam within the drum to the outer pressing surface, which is the outer surface of approximately the upper half 14 of the drum or casing.

The pressing operation is accomplished by drawing the article to be pressed back and forth over the pressing surface of the apparatus first one side and then the other being placed downward over the row of holes 12 in the top thereof. To accomplish this the article is gripped at the ends by the operator, one end in each hand, and is alternately pulled downward by one hand and then by the other as shown in Figure 3. The outer surface of the drum is preferably polished and nickel-plated so that there are no rough places thereon, whereby the pressing surface is smooth for drawing the article thereover.

Having described my invention I claim as new:

1. A polished pressing apparatus comprising a cylindrically-shaped casing, a

pressing surface on the outer face thereof over which the articles are drawn back and forth when being pressed, a port admitting steam to said casing to heat the pressing surface, a plurality of steam outlets in said pressing surface, and a partition wall in said casing dividing the casing longitudinally thereof into upper and lower chambers to prevent the direct passage of steam from 5 said port to said outlets and an opening in the said wall remote from said steam inlet port to permit the passage of the steam from the lower chamber into the upper chamber and through the steam outlets in the pressing 10 surface.

2. A pressing apparatus comprising a casing, a polished pressing surface on the outer face thereof, over which the articles are drawn back and forth when being pressed, a partition wall in said casing dividing the casing into longitudinal chambers, a steam inlet port in one of said chambers, a plurality 15 of steam outlets in the other chamber, the said chamber having the steam port constituting a drying chamber for the steam and an opening between said chambers whereby the steam in a relatively dry condition may 20 pass into the other chamber to heat the pressing surface and through the steam outlets to steam the article while being pressed.

rality of steam outlets in the other chamber extending through the pressing surface, and an opening in the said partition wall to 25 permit the passage of steam from the one chamber to the other and through the steam outlets in the pressing surface.

3. A pressing apparatus comprising a casing, a pressing surface on the outer face thereof, over which the articles are drawn back and forth when being pressed, a partition wall in said casing dividing the casing into longitudinal chambers, a steam port in one of said chambers and a plurality 30 of steam outlets in the other chamber, the said chamber having the steam port constituting a drying chamber for the steam and an opening between said chambers whereby the steam in a relatively dry condition may 35 pass into the other chamber to heat the pressing surface and through the steam outlets to steam the article while being pressed.

NICHOLAS BENENATI.
